UNITED STATES PATENT OFFICE.

JOHN JAMES HEYS, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-MOLDING MACHINE.

1,291,880.

Specification of Letters Patent. Patented Jan. 21, 1919.

Application filed November 2, 1917. Serial No. 199,849.

To all whom it may concern:

Be it known that I, JOHN J. HEYS, a citizen of the United States, residing at Lynn, in the county of Essex and State of Massachusetts, have invented certain new and useful Improvements in Sole-Molding Machines; and I do hereby declare the following to be a full, clear, and exact description of the invention, such as will enable others skilled in the art to which it appertains to make and use the same.

The present invention relates to molding machines and more particularly to machines of this type employed for molding soles prior to their incorporation in a boot or shoe.

In molding soles which have been tempered or softened by immersion in water or other suitable liquid it is desirable to provide means for collecting and disposing of the liquid which oozes from the sole under pressure to prevent this liquid from coming into contact with and corroding the moving parts of the machine.

The object of the present invention, therefore, is to provide means for inclosing the lower mold in a manner to insure the collection of all of the liquid which is squeezed from the sole, which at the same time affords an adequate support for the mold during the sole pressing operation.

With this object in view a feature of the invention contemplates the provision of a single integral casting having walls which inclose the mold, a boss co-extensive in area with the mold and adapted to accord a firm support for the latter, and gutters surrounding the boss and sloping toward a discharge opening which passes through the base of the casting.

A further feature of the invention consists in the combination with a sole mold, of a slide supporting the mold, inclosing walls surrounding the mold, a discharge opening adapted to lead liquid away from and below the slide, and gutters surrounding the mold within the walls and sloping toward and communicating with the discharge opening.

In the simplest and most efficient form of the invention which has yet been devised, the improved receptacle or pan is adapted for attachment to existing machines, and to

this end is formed as a single integral casting having a boss extending above and below the base of the pan and adapted to rest upon the mold slide and support the mold directly from the slide. This pan is secured to the slide in any suitable manner and is adapted to receive the usual type of mold having a pin-receiving recess in the bottom and a slot in one end. This construction, accordingly, serves the dual function of a support for the mold and a receptacle for inclosing the mold and collecting the liquid which oozes out from between the molds when under pressure.

It is to be understood that the present invention in its broader aspects is not limited in its application to a machine for molding soles, but is capable of embodiment in various types of machines adapted for molding or shaping articles which are in a moistened or tempered condition.

In the accompanying drawings illustrating the preferred form of the invention, Figure 1 represents a partial side elevation of a molding machine embodying the several features of the invention in their preferred forms; Fig. 2 is a plan view of the improved drip pan; Fig. 3 is a cross section in elevation of the drip pan with a mold supported thereon in a position of pressure; and Fig. 4 is a detail illustrating a cross section of the pan taken upon the line 4—4 of Fig. 2.

The illustrated embodiment of the invention is shown in connection with a machine of the type disclosed in the co-pending application of Heys, Serial No. 26,551, filed May 7, 1915. This machine comprises a stationary pressing form 1 and a co-operating sole supporting form 2, which are adapted, as shown clearly in Figs. 1 and 3 of the drawings, to impart the desired shape to a sole prior to its incorporation in a boot or shoe. The lower mold 2 is carried upon a slide 4 which is supported in a head 5 moving virtually between guide rods 6. According to the usual operation of machines of this type the vertical movement of the head 5 causes a simultaneous horizontal movement of the slide 4 relative to the head to carry the lower mold 2 into alinement with the upper mold 1, the lower mold being positioned at the front of the machine out

of alignment with the upper mold for the convenient application and removal of the shoe soles.

During the sole molding operation the liquid which is squeezed out of the sole runs down upon the machine if no provision is made for collecting it. This tends to corrode the moving parts of the machine, more particularly the ways in which the slide 4 moves, and is, in consequence, highly objectionable. It is essential that this liquid shall be collected and that the receptacle or pan may be embodied in the machine without interfering with their normal operation or otherwise detracting from the efficiency. To this end the present invention contemplates the provision of a drip pan surrounding the lower mold and in which the latter is supported, and having no provision for the egress of liquid therefrom except through a suitably disposed discharge opening. According to the present invention the pan consists of a single integral casting made of a material sufficiently strong to withstand the pressure of the mold during the operation of the machine and having suitably disposed members for locating and positioning the mold within the pan.

In the illustrated embodiment of the invention a drip pan 10 is supported upon the mold slide 4 and is secured to the slide through a plurality of threaded fastenings 11. The pan is provided with a raised boss 12 forming a base upon which the mold is supported, and provided with a pin 13 adapted to be received within the usual longitudinal slot 14 formed in the rear end of the mold and serving to position the mold relative to the pan. The pan is completely inclosed by a wall 15 which at the sides projects slightly above the highest portion of the mold to insure the collection of liquid squeezed out of the sole when the mold is in pressing position. Extending longitudinally of the pan upon opposite sides of the base are a pair of gutters 17 which slope toward one end of the pan in which is located a discharge opening 19, connected with a suitable discharge pipe 20. The two gutters 17 are connected at the discharge end by a gutter 21 forming, in effect, a single gutter communicating with the discharge opening. The entire pan is a single casting having the base, wall and gutters formed integral therewith and effectually preventing the escape of moisture on to the mold slide 4 or other moving parts of the machine. It will be noted from an inspection of Figs. 3 and 4 that the boss 12, which forms the base portion, extends below the under side of the pan and is provided with a face resting upon the mold slide and affording a firm foundation for that portion of the pan which is directly subjected to the pressure of the mold. The end of the pan opposite

the base is provided with a plurality of depending feet 22, formed integral therewith and engaging with the mold slide, as shown clearly in Figs. 1 and 3.

The pan is preferably formed of cast iron and is amply strong to support the mold when under pressure. Owing to the shape of the molds the pressure exerted has both a vertical and a longitudinal component, the latter tending to shift the mold lengthwise of the pan. In order to properly position the mold and resist this tendency to move longitudinally on the part of the mold, a positioning stud 25 is, accordingly, secured to the pan and is received in the usual opening or hole 26 formed in the bottom of the mold. This stud is threaded into the base portion of the pan and is preferably made of steel of sufficient strength to prevent shearing under the longitudinal pressure exerted by the mold.

This construction, then, has the advantage that a simple and effective provision is made for insuring the collection of moisture and preventing the moisture from coming in contact with the mold slide either through capillary attraction or otherwise, and an adequate support for the mold is provided.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A sole molding machine, comprising a mold, a slide supporting the mold, inclosing walls surrounding the mold, a discharge opening, and gutters surrounding the mold within the walls and sloping toward and communicating with the discharge opening to cause liquid which drains down the mold to be discharged through the opening.

2. A sole molding machine, comprising a mold, a slide supporting the mold and a pan in which the mold is received, comprising walls inclosing the mold, a base portion supporting the mold, positioning devices on the base portion, a discharge opening and gutters surrounding the base portion within the walls and sloping toward and communicating with the discharge opening.

3. A drip pan for molding machines, comprising a single integral casting having walls adapted to inclose a mold, and a base portion provided with a boss adapted to support a mold and with a mold positioning device, the base portion having gutters surrounding the boss and sloping toward a discharge opening formed in the base.

4. A drip pan for molding machines, comprising a base portion provided with an in-

tegral boss and mold locating devices, in-closing walls formed integral with the base portion, gutters formed in the base portion and communicating with a discharge opening, and a mold positioning pin detachably connected to the base portion and adapted to be received in a corresponding opening formed in the mold.

5. A sole molding machine, comprising a slide, a mold supported by the slide, a pan

interposed between the mold and slide and having a base portion provided with a boss substantially co-extensive in area with the mold and serving to directly support the mold upon the slide, mold positioning devices upon the base portion of the pan, and walls formed upon the base portion and in-closing the mold. 15

JOHN JAMES HEYS.
